UNITED STATES PATENT OFFICE.

WILLIAM H. THOMAS, OF FULTON, MISSOURI.

STREET DELIVERY APPARATUS.

SPECIFICATION forming part of Letters Patent No. 425,469, dated April 15, 1890.

Application filed July 24, 1889. Serial No. 318,538. (No model.)

To all whom it may concern:

Be it known that I, WILLIAM H. THOMAS, a citizen of the United States, residing at Fulton, in the county of Calloway and State of Missouri, have invented certain new and useful Improvements in Street Delivery Apparatus; and I do declare the following to be a full, clear, and exact description of the invention, such as will enable others skilled in the art to which it appertains to make and use the same, reference being had to the accompanying drawing, and to the letters of reference marked thereon, which forms a part of this specification.

This invention relates to delivery service, and aims to furnish a convenient and simple means of delivering milk, butter, meat, groceries, &c., from the delivery-wagon to residence without the driver having to dismount or call on the servant or lady of the house, the device being operated wholly by the deliverer.

The improvement consists of the novel features which will be hereinafter more fully described and claimed, and which are shown in the annexed drawing, in which the figure is a side view showing the operation of the invention by dotted lines.

A represents the front of the house; B, the post at the curb or side of the roadway; C, the track-wire, and g the carrier.

The operating-lever D is pivoted between its ends to post B at H, and the track-wire is attached to the outer end of the lever and passes over pulley e on the top of post B and around pulley h on the outer end of lever D. To facilitate the operation of the lever, that part of the track-wire which works over pulleys e and h is replaced by a chain 40 which will readily adapt itself to the line of tension.

The spring-bumper K at the inner end of the track-wire is provided with a bell L, which sounds an alarm when the carrier strikes 45 against the bumper.

The operation is as follows: The carrier normally rests against the bumper, and when goods are to be delivered the lever is operated to lower the outer end of the track-wire,

when the carrier will gravitate to the outer end of the track, where it is loaded. The lever is now operated to elevate the outer end of the track-wire, and the carrier with its load will gravitate toward the house. The carrier, striking the spring, will be stopped gently 55 and sound an alarm. The outer end of the lever will be held to the post by suitable catch, as the hook and eye J and j, thereby holding the outer end of the track-wire elevated.

It will be observed that the lever D is adapted to move about its pivot H in the plane of the track-wire C, and that the inner end of the track-wire moves around the pulley e to equalize the tension on the track-wire 65 as lever D is moved to change the inclination of the said track-wire.

I claim—

1. The combination, with the post B, having pulley e, and the lever D, pivoted between 70 its ends to post B, and having pulley h, of the track-wire made fast at its inner end to a suitable support and having its outer end passed around pulley h on lever D, around pulley e on post B, and fastened at its outer 75 end to the outer end of lever D, the lever and track-wire being in the same plane, substantially as and for the purpose described.

2. The herein shown and described means for delivering goods from the roadway to the 80 house and sounding an alarm, consisting of post B, having pulley e, the lever D, pivoted between its ends to post B and having pulley h at its inner end, the track-wire secured at its inner end to the house and having its 85 outer end passing around pulleys h and e and secured to the outer end of lever D, the lever and track-wire being in the same plane, the carrier on the track-wire, and the spring-bumper attached to the house and provided 90 with a bell, substantially as set forth.

In testimony whereof I affix my signature in presence of two witnesses.

WILLIAM H. THOMAS.
